TRAFFIC CONTROL SYSTEM

Vernon Durbin, Newton, Mass., assignor to The Gamewell Company, Newton Upper Falls, Mass., a corporation of Massachusetts

Application June 12, 1929, Serial No. 370,306

17 Claims. (Cl. 177—337)

The present invention relates to traffic control systems for intersecting ways.

A common type of traffic control system embodies a uniform time sequence operation by which "stop" and "go" signals are flashed at definite time intervals without regard for the density of traffic on either of the intersecting ways. This type of system is objectionable in that it causes unnecessary delay to vehicles approaching the "stop" signal while there is no traffic on the cross-way.

Another type of automatic system employs a control which is normally set to permit flow of traffic on the more important way, while providing for an automatic shift of signals for a short period upon approach of a vehicle on the less important way. The automatic change of signals is usually effected acoustically or photo-electrically. Such systems are open to the disadvantage that a stream of traffic on the less important way may hold up vehicles on the more important way for an indefinite period. If the mechanism becomes out of order, as is likely to happen, because of the delicacy of the mechanism, traffic may be delayed for long periods. Moreover, the signals are subject to change by tampering by irresponsible individuals.

One object of the present invention is to provide automatic means whereby a vehicle approaching the intersection on either way may act to gain control of the system to display the "go" signal, but wherein the maximum time within which traffic on one way may hold control of the system is limited.

Another object of the invention is to provide a system in which the signals normally change in timed sequence but in which the normal timing may be disturbed to permit a waiting vehicle to pass.

A further object of the invention is to provide responsive means which is sufficiently sensitive to gain control of the system by passing or waiting traffic, which is not likely to become out of order, and which cannot easily be rendered ineffective by tampering.

With these and other objects in view as will hereinafter appear, one feature of the invention comprises the combination of vehicle responsive means whereby a vehicle on approaching the intersection may act to bring about a change of signals if the "go" signal is not already displayed, together with sequential timing means whereby the signals are changed in any event at the end of a predetermined period. According to this feature, it is therefore impossible for traffic on one

way, no matter how heavy it may be, to hold indefinite control of the system to the exclusion of waiting vehicles on the other way.

Another feature of the invention comprises the combination of normally operating means to change the signals in timed sequence, together with means operating upon the approach of a vehicle to the "stop" signal for effecting a nearly immediate advance of the change of signals in the event that there is no traffic on the cross-way. As an additional feature, the invention also provides for holding control of the system for a short period after the passage of a vehicle through the intersection. Thus, a vehicle passing the "go" signal on one way holds control of the system for that way for a period of a few seconds during which time a waiting vehicle stopped on the intersecting way may not gain control of the system. Thus, continuous traffic on the way which shows the "go" signal may hold control of the system to the exclusion of vehicles on the other way but only for a maximum period determined by the normally timed sequential operation of the system. The means by which a vehicle gains control of the system to disturb the normal timing of the signals is preferably automatic in that it responds to the presence of the vehicle without the necessity of any act on the part of the driver. The features of the invention as above described, however, are not limited to such automatic responsive means, but may be constructed to be operated manually, if desired.

As a further feature, the present invention contemplates a simple and effective form of responsive means which operates upon the approach or presence of a vehicle in its vicinity. This means comprises a normally balanced induction bridge, the characteristics of whose magnetic circuit may be altered by the presence of a body of magnetic material. Thereupon, the bridge becomes unbalanced and through the energization of the detector circuit, it is enabled to set the signal changing apparatus into operation. The responsive means of the present invention is advantageous in that while it is sufficiently sensitive to operate upon the approach of a considerable body of magnetic material, such as a motor vehicle, it is not subject to unbalance by tampering.

Other features of the invention consist of certain novel features of construction, combinations and arrangements of parts hereinafter described and particularly defined in the claims.

In the accompanying drawings illustrating the preferred form of the invention, Fig. 1 is a diagrammatic view showing the positions of the sig-

nal device and the responsive means at an intersection of two ways; Fig. 2 is a plan view of one of the responsive devices; Fig. 3 is an elevation of one of the responsive devices set in the 5 roadway; Fig. 4 is a plan view of the operating and controlling mechanism; Fig. 5 is a diagram of the electrical connections; Fig. 6 is a detail section on line 6—6 of Fig. 4; Fig. 7 is a detail sectional view on line 7—7 of Fig. 4; and Fig. 8 10 is a development of the advancement controlling cam.

General description.—The invention is herein 15 illustrated and described as embodied in a system for traffic control at two intersecting ways shown in Fig. 1 as a north-south way—NS and an east-west way—EW. A signal tower 10 of any usual or preferred form is located at the center of the intersection. This tower contains two sets of lights, one of which is adapted 20 to show on the north-south way and the other on the east-west way. Each set comprises three lights—a green light as a "go" signal, a yellow light which is displayed near the end of the green signal to indicate that the red is about to 25 come on, and a red light as a "stop" signal. The lights are normally operated sequentially by a predetermined time control in the usual fashion of automatic signals. The relative durations of the different signals may be adjusted in any 30 desired manner, preferably with regard to the relative densities of traffic on the intersecting ways. The following specific sequence will be assumed in the description of the invention. The green light shows on NS for 40 seconds and the green 35 and yellow together for 5 seconds. During this entire period of 45 seconds, the red light shows on EW. Then on NS the green and yellow lights are extinguished and the red light comes on for 45 seconds. For the first 40 seconds of this period, 40 the green light shows on EW and for the remaining 5 seconds, the yellow light comes on with the green.

The sequential control is effective to operate 45 the signals in the manner above described only 50 when there is no traffic in either direction or when no vehicles arriving at the intersection meet the red light or when there is a steady flow of traffic in both directions. In order to minimize the delay in the event of the approach of 55 a vehicle to the red light while there is no traffic in the other direction, there is superposed on the sequential control an automatic control which is responsive to the approach of a vehicle and which initiates the operation of means to effect a nearly 60 immediate change of signals. Thus, a vehicle approaching the intersection gains control of the system through the automatic responsive means. If the red light is showing upon approach of the vehicle on NS, for example, while 65 there is no cross traffic on EW, the normal time sequence is thrown out, the EW traffic signal immediately displays the green and yellow lights for 5 seconds, after which time the EW signal changes to red, and the NS signal to green. It is 70 to be noted, however, that a vehicle approaching the red light gains immediate control only in the event that no cross traffic is passing or has passed within a predetermined period. Any vehicle approaching the intersection whether meeting the red or the green light, gains control for a predetermined time, say, about 3 seconds. Thus, if a vehicle approaches the red light on NS 75 within 3 seconds after the passage of a vehicle on EW, the change of signals is delayed until the 3

seconds has elapsed. The waiting vehicle must therefore wait out the remainder of the 3 seconds, as well as the 5 seconds, during which the caution signal is displayed on EW. If during the 3 seconds interval in which NS has not yet gained control of the system, another vehicle passes on EW, the change will be delayed for another period of 3 seconds. Accordingly, a steady stream of traffic on EW will not permit NS to gain control of the system and EW traffic will be permitted 10 to pass unimpeded. The maximum length of time in which the EW traffic may thus hold control of the system is, however, determined by the normal timed sequence of the lights. That is to say, no matter how heavy the traffic may be 15 on EW, a waiting vehicle on NS is not obliged to wait more than 45 seconds.

Responsive devices.—The preferred form of responsive device or initiating means by which an approaching vehicle gains control or attempts 20 to gain control of the system is shown in Figs. 2 and 3. This device comprises a sensitive induction balance arranged in the general form of a Wheatstone bridge which is normally in balanced 25 condition but which is magnetically and electrically unbalanced by the presence of a body of magnetic material in proximity thereto. The bridge comprises four inductance coils 12, 14, 16 and 18, mounted on the corners of a hollow rectangular base 20. Each coil is provided with an iron core 22. Four of these devices are mounted in the roadway near the intersection, as shown in Fig. 1, so that an approaching vehicle must necessarily pass over one of them. The devices 30 are embedded in the roadway so that the upper 35 surfaces of the magnetic cores are flush with the road surface. The base 20 is of such dimensions that the magnetic circuits of the inductances will be disturbed by the passing of a vehicle over or near them. Preferably the sides of the base 40 20 are somewhat greater than the width of an ordinary passenger vehicle. The inductances of each device are energized by alternating current. The cores of diagonally opposite inductances 12 and 18 are magnetized in the same direction 45 while the cores of inductances 14 and 16 are magnetized oppositely to those of inductances 12 and 18. The inductances are electrically connected as shown in Fig. 5, adjacent coils forming diagonally opposite arms of the bridge. Thus, for the 50 south responsive device indicated at s in Fig. 5, the arms 12 and 14 are electrically connected as diagonal arms and the coils 16 and 18 form the other diagonal arms. The bridge is connected to alternating current mains 24 and 25. The detector circuit is connected in the manner usual to 55 bridges and includes a relay 26 adapted to attract an armature 28 to close initiating switch contacts 30. Inasmuch as the relay operates most effectively on direct current, a rectifier 32 is included 60 in series with the relay coil. Similarly, the east responsive device e is connected to operate a relay 34 which controls an armature 36 adapted to close an initiating switch 38. The north and 65 west responsive devices are not shown. The detector circuit of the north device leads to a relay winding 40 which controls the armature 28 and the detector circuit of the west device leads to a relay winding 42 which controls the armature 36. 70

When there is no traffic in either direction, the responsive devices are inactive, the detector circuits being de-energized and the armatures 28 and 36 being in retracted position. When a ve- 75

hicle comes over one of the responsive devices, the magnetic circuit characteristics are changed, thereby unbalancing the bridge. Preferably the base 20 of each bridge is of slate or other non-magnetic material, in order that the variation introduced by the presence of a vehicle will be proportionately large. Upon electrical unbalancing of one of the bridges, either the switch 30 or the switch 38 will be closed. These switches constitute a part of the initiating circuits by which a vehicle in proximity to one of the responsive devices acts to gain control or to endeavor to gain control of the system.

In the event that the detector current caused by unbalance of the bridge is too small to actuate the relay, amplifiers of any usual form may be employed.

As shown in Fig. 5, the responsive devices are continuously energized from the alternating current power mains. Obviously, however, the sensitivity of the system is materially increased if the bridges are energized with current of relatively high frequency. However, sufficient sensitivity is obtained with commercial alternating current without making the devices so sensitive as to be unbalanced by the accidental presence of small bodies of magnetic material.

Timed sequence operating system.—The signal tower has the two sets of lamps indicated in Fig. 5, the red, yellow and green lamps—R, Y and G for the NS way, and the corresponding lamps R', Y' and G' for the EW way. For the normal sequential control of the system, these lights are operated by four cams, namely, a master cam 44 and a yellow light control cam 46 for the NS system, and a similar set of cams 48 and 50 for the EW system. The cam 44 controls a switch 52 having a central movable contact 54 and two stationary contacts 56 and 58. The cam 48 of the EW system controls a similar switch 60. The cams 46 and 50 operate double contact switches 62 and 64 respectively. Considering the NS system, when the movable switch contact 54 is closed on the lower contact 58, the green light shows and when closed on the upper contact 56, the red light is displayed. One contact of the switch 62 is connected to the lower contact 58 of the switch 52 and the other contact of the switch 62 is connected to the yellow light. Electrical connections are suitably made to the lines 24 and 25 for lighting the lamps. The cams of the EW system are identically arranged but displaced 180° from the corresponding NS cams. The cams are mounted on a shaft 66 on one end of which is mounted a ratchet 68 (see Figs. 4 and 7). The ratchet is engaged by pawls 70 carried on a rotating arm 72 and pressed into engagement with the ratchet by springs 74. The carrier arm 72 is mounted on a shaft 76 which is continuously rotated by a motor 78 through reduction gearing 80. In normal operation, the shaft 66 rotates continuously with the shaft 76, thereby driving the light control cams at a uniform rate.

In the specific example assumed above, wherein the red and green lights show alternately for periods of equal length, the cams 44 and 48 are exactly similar but are displaced 180°. Each of these cams is arranged to close the movable contact on the upper contact of the switch for half a revolution and to close it on the lower contact for the other half revolution. The cams 46 and 50 are also displaced 180° apart. Each has a dwell 78 of 20° to close its corresponding switch 62 or 64 for 5 seconds to display the yellow light.

Automatic responsive control.—The closing of

either of the initiating switches 28 or 30 by the presence of a vehicle in proximity to one of the responsive devices initiates the operation of apparatus to advance the normal sequential control in order that a change of lights may be more quickly effected under some circumstances. To this end, the switch 30 is connected in series with an electro-magnet 90 which is adapted to attract an armature 92. Similarly, the switch 38 controls energization of an electro-magnet 94 which is adapted to attract an armature 96. The magnet 90, however, is adapted to be de-energized independently of the operation of the switch 30 at a predetermined time prior to the change of signals from green to red on NS, and similarly, the magnet 94 is arranged so that it cannot be energized for a short period preceding the change on EW. For convenience, the respective magnets are arranged to be positively de-energized at such times as the green and yellow caution signals are displayed on their corresponding ways. To this end, the magnet 90 connects through a wire 98 to a switch 100 which is operated by a cam 102 also mounted on the shaft 66. The cam 102 maintains the switch 100 closed for 340° of its revolution and is provided with a depression 104 of 20° which opens the switch 100 at the same time that the cam 46 closes the switch 62. Similarly, the electro-magnet 94 is controlled by a wire 106 in series with a switch 108 which is controlled by a cam 110 having a depression 112 to open the switch at just the time that the switch 64 is closed by the cam 50. Thus, two initiating circuits are provided:—for the NS way from the main 24 through detector switch 28, relay magnet 90, wire 98, switch 100, and wire 113 to the main 25; and for the EW way, from the main 24 through wire 114, switch 38, relay 94, wire 106, switch 108, and wire 113 to the main 25.

The armatures 92 and 96 are of the peculiar form shown in Fig. 6, and are so arranged as to be interlocking, that is to say, so that when one armature is attracted, it mechanically prevents attraction of the other armature. The armature 96 is pivoted to swing freely on the drive shaft 76 and it is provided with an inwardly extending lower end 115 which tends to move the armature into retracted position by gravity. The armature 92 is similarly constructed and is freely pivoted upon a shaft 116 which is driven from the shaft 76 but in the opposite direction by means of gears 118 and 120. Each of the armatures has a blocking foot 122 which prevents attraction of the other armature when it is itself attracted. Pivoted on each armature is a pawl 124 which engages its corresponding gear wheel. The upper ends of the armatures are connected by a spring 126. It will be seen that if both armatures are in retracted position, one of them may be attracted by its magnet unimpeded by the other armature. During an attracting movement, the pawl slides freely over the gear. However, retraction of an armature after the magnet is de-energized is retarded by the engagement of the pawl with the gear for a period of time depending upon the rate of the shaft. Thus, after one of the armatures has been attracted, the other armature cannot be moved into attracted position for a period of time determined by the retarded retraction of the first armature. This is preferably a period of about 3 seconds, for which time a vehicle that has passed holds control of the system to the exclusion of a vehicle on the cross-way.

Double contact switches 128 and 130 are mount-

ed adjacent to the respective armatures 92 and 96. These switches are normally open but are adapted to be closed by their armatures when the latter are attracted. To this end, each armature carries an insulating pin 132 adapted to engage the upper switch contact.

5 Mounted on the shaft 66 is a barrel cam 134, a development of which is shown in Fig. 8. The 10 cam has a groove 136 to receive a pin 138 upon a cam follower lever 140 which is pivoted at 142. This groove is timed to move the lever in synchronism with the light control cams. The sloping part 144 of the groove engages and moves the lever during the showing of the red light on NS. 15 This groove is 160° in length which corresponds to 40 seconds in the example given above. The straight part of the groove 146 during which no movement is imparted to the lever is 20° corresponding to a duration of 5 seconds. The 20 inclined portion 148 is similar to the portion 144 but arranged to engage and move the lever during the showing of the red light on EW. The dwell 150 which holds the lever stationary is similar to the dwell 146. The upper end of the lever carries two armatures 152 and 154 which cooperate respectively with the cores 156 and 158 of electro-magnets 160 and 162. During the normal sequential operation of the system, the magnets are de-energized and the armature swings idly over them. One or the other of the magnets is adapted to be energized by the closing of one of the switches 128 and 130. The switch 128 is connected in series with the electro-magnet 162 which in turn is connected in series with a switch 30 35 40 45 50 55 60 65 70 75 164 controlled by a cam 166 on the shaft 66. The cam 166 is exactly similar to the light control cam 44 of the NS system and is so arranged that the switch 164 is open when the green light is showing on NS, this being a time when a vehicle approaching on NS does not require a change of signal. Similarly, the switch 130 is connected in series with the electro-magnet 160 and a switch 168 which is controlled by a cam 170. The switch 168 is closed when the red light is showing on EW and is open when the green light is showing. The switches 128 and 130 are suitably connected to one side 24 of the mains and the switches 164 and 168 are suitably connected to the other side of the mains 25. Thus, two advancement controlling circuits are provided, one for each way. For the NS way, the circuit comprises the advancement control switch 128, the magnet 162 and the switch 164. For the EW way, the circuit comprises the advancement control switch 130, the magnet 160 and the switch 168. Considering the NS system, whenever the switches 128 and 164 are simultaneously closed (the lever 140 being then controlled by the cam groove 144), the magnet 162 is energized, thereby immediately attracting the lever 140 to its extreme position. Inasmuch as the cam groove is of steep pitch, the cam is advanced by the lever until the latter engages the dwell 146 of the cam groove. Therefore, the ratchet 68 overruns the pawl 70, immediately advancing the cams to such a position that the yellow light is displayed on the EW way. It will be understood that this action for NS can occur only when the switches 128 and 164 are simultaneously closed, that is, only at a time when the red light shows on the NS way and the green light on the EW way. Similarly, the corresponding switches 130 and 168 can be simultaneously closed only when a vehicle approaches the red light on EW. The immediate advance of the shaft 66 and its associated cams lights the yellow

light in combination with the green on the EW way for 5 seconds, after which time the red light on the NS way changes to green. During the 5 second interval, the switch 108 is opened, thus opening the EW initiating circuit, so that no further change can be brought about by a vehicle approaching on EW. Therefore, if a vehicle approaching the red light on NS is able to gain control of the system by closing switch 128, its maximum wait will be 5 seconds. However, it may be that the approach of the vehicle will be ineffective to close the switch 128 because of the fact that the armature 92 may be blocked by the armature 96 in attracted position.

Operation.—The operation of the system under different conditions of approach of vehicles on the two ways will now be explained.

When there is no traffic in either direction, the lights will operate in normal timed sequence.

When a vehicle approaches the green light, the circuit conditions are as shown in Fig. 5. The green light has just come on for NS, and the red light for EW. A vehicle approaching on NS has attracted the armature 92, the magnet 90 having been energized because the switch 100 is closed. The switch 128 is closed by the armature, but is ineffective to energize the magnet 162 because the switch 164 is open. There is, therefore, no change in the lights; the only effect of the passage of this vehicle is to hold control of the system for NS traffic for the period that the armature 92 mechanically blocks the armature 96 (say, 3 seconds). An EW vehicle now approaching, although it may cause the magnet 94 to be energized, cannot succeed in attracting the armature 96 to close the switch 130 until the three seconds' period has elapsed. If during that interval, another NS vehicle approaches, it again attracts the armature 92 and holds control for NS for another three seconds. The longest period, however, for which NS traffic may continuously hold the green light is determined by the normal timing of the system (forty seconds, with five seconds additional for the green and yellow caution signal). It will be noted that inasmuch as the switch 100 is open when the green and yellow signal shows on NS, a vehicle on NS is unable either to gain or to hold control during the display of that signal.

Attention may be here directed to the fact that it is not essential for the switch 100 to operate in exact synchronism with the display of the caution signal. The purpose of the switch 100 is to open the NS initiating circuit at a sufficiently early time to permit the armature 92, if already attracted, to return to its fully retracted position prior to showing of the red signal on NS, thus unblocking the armature 96 and permitting a vehicle on EW to gain control of the system. The period during which either the switch 100 or the switch 108 is required to be opened is therefore the time necessary for complete retraction of the armature from fully attracted position, no matter what period may be determined upon for the showing of the caution signal. When the retraction period is less than the duration of the caution signal, the periods may be and preferably are coincident, as in the construction above described. It will be noted that the yellow light may be omitted altogether, the signals changing directly from red to green, in which case also the provision for opening the initiating circuit near the end of the display of the green signal forms an important feature.

When a vehicle approaches the red light on

NS, the armature 92 is attracted, if it is not blocked by the armature 96. Thereupon, the magnet 162 is energized, and the lever 140 is immediately attracted to its lowest position, thus advancing the shaft 66 faster than the drive shaft 76, and bringing the cams to such a position that the yellow light is flashed with the green on EW. After five seconds, EW changes to red and NS changes to green to permit the waiting vehicle to pass. Thereafter, the signals continue to flash in normal timed sequence until disturbed again in the manner above described.

In the event that traffic on both ways is steady, neither will be able to gain control to throw the normal sequence out of operation.

It will be seen that the invention provides a control which operates practically in accordance with the relative densities of traffic on the intersecting ways. Moreover, although permitting nearly unimpeded progress of steady traffic on one way, it does not disregard the rights of a single driver endeavoring to cross a busy thoroughfare. The longest time which a vehicle is required to wait is the normal time of display of the red light (forty-five seconds)—on the other hand, a vehicle approaching the red light may be permitted to pass in five seconds.

In the event that the automatic responsive means becomes out of order, the system as a whole is not rendered inoperative but works on its time sequence basis. If one of the bridges should become more or less permanently unbalanced, as by the breaking down of a car near it, it would not permanently hold control of the system to the exclusion of cross traffic.

Although the system has been illustrated and described as employing an inductive bridge responsive means, which in itself forms a feature of the invention, it will be understood that the operating mechanism is not limited to control by any specific responsive means. Viewed in its broader aspects, the responsive devices form a means for closing the initiating circuits at the switches 128 and 130, and for this purpose any suitable devices may be employed. For example, the initiating switches 28 and 36 might be closed manually by the driver of the vehicle.

Furthermore, such inductive bridge responsive means or detector mechanism is not herein specifically claimed, as same forms the subject matter of my co-pending application, Serial No. 38,640, filed July 2nd, 1936, as a division hereof.

Although a specific description has been given of one form of apparatus, employing signals of certain color operating normally in time sequences of equal duration and for definite periods, it will be understood that signals of any desired form, color and arrangement may be employed and operated in any desired timing and sequence.

Having thus described the invention, what is claimed is:

1. A traffic control system for intersecting ways having, in combination, a right of way signal device including a set of signals for each way, normally operative signal control mechanism to change the signals sequentially, driving means normally acting to drive the signal control mechanism at a uniform rate, and means involving traffic responsive mechanism for advancing the signal control mechanism with respect to the driving means to advance the change of signals out of normal sequence without thereby affecting the order of sequence.

2. A traffic control system for intersecting ways

having, in combination, a right of way signal device including a set of signals for each way, signal controlling mechanism normally operating to change the signals in timed sequence, with predetermined timed intervals between changes 5 driving means normally acting to drive the signal controlling mechanism at a uniform rate, an initiating circuit for each way, an advancement controlling circuit for each way, a switch in each advancement controlling circuit, means operated 10 upon closure of the initiating circuit to close the corresponding advancement controlling switch and to obstruct closure of the other advancement controlling switch, and means operated by closure of an advancement controlling circuit to 15 cause the signal controlling mechanism to overrun the driving means whereby to cause cancellation of substantially all of the unexpired portion of a then effective prechange interval.

3. A traffic control system for intersecting ways 20 having, in combination, a right of way signal device including a set of "stop" and "go" signals for each way, signal operating mechanism, driving means for the signal operating mechanism acting normally to change the signals in timed 25 sequence, with predetermined timed intervals between changes an initiating circuit for each way, a relay in each initiating circuit, having an armature, means for interlocking said armatures when one is attracted so that the other cannot be 30 attracted, and advancement controlling mechanism operable upon a predetermined positioning of an armature to advance the signal operating mechanism with respect to the driving means whereby to cause cancellation of substantially all of the 35 unexpired portion of a then effective prechange interval.

4. A traffic control system for intersecting ways having, in combination, a right of way signal device including a set of "stop" and "go" signals 40 for each way, signal operating mechanism, driving means for the signal operating mechanism acting normally to change the signals in timed sequence, with predetermined timed intervals between changes, an initiating circuit for each way, 45 a relay in each initiating circuit, having an armature, means for interlocking said armature when one is attracted so that the other cannot be attracted, means to retard retraction of an armature after being attracted, and advancement 50 controlling mechanism operable upon a predetermined positioning of an armature to advance the signal operating mechanism with respect to the driving means whereby to cause cancellation of substantially all of the unexpired portion of a 55 then effective prechange interval.

5. A traffic control system for intersecting ways having, in combination, a set of "stop" and "go" signals for each way, signal operating mechanism, driving means for the signal operating 60 mechanism acting normally to change the signals in timed sequence, with predetermined timed intervals between changes, an initiating circuit for each way, a relay in each initiating circuit 65 having a pivoted and normally retracted armature, interlocking means preventing concurrent attraction of said armatures, a pawl on each armature, continuously rotating wheels engaged by said pawls for retarding retraction of a previously attracted armature, and advancement 70 controlling mechanism operable upon a predetermined positioning of an armature to advance the signal operating mechanism with respect to the driving means whereby to cause cancellation 75

of substantially all of the unexpired portion of a then effective prechange interval.

6. A traffic control system for intersecting ways having, in combination, a set of "stop" and "go"

- 5 signals for each way, signal operating mechanism, driving means for the signal operating mechanism acting normally to change the signals in timed sequence, with predetermined timed intervals between changes, an initiating circuit for
- 10 each way, a relay, having an armature, in each initiating circuit, means for interlocking said armatures when one is attracted so that the other cannot be attracted, an advancement controlling circuit for each way, means for closing
- 15 an advancement controlling circuit when the armature of its corresponding relay is attracted and the "stop" is displayed, and signal advancing mechanism to advance the operating mechanism with respect to the driving means whereby to cause cancellation of substantially all of the unexpired portion of a then effective prechange interval.
- 20

7. A traffic control system for intersecting ways having, in combination, a set of "stop" and "go"

- 25 signals for each way, signal operating mechanism, driving means for the signal operating mechanism acting normally to change the signals in timed sequence, with predetermined timed intervals between changes, an initiating circuit
- 30 for each way, a relay, having an armature, in each initiating circuit, means for interlocking said armatures when one is attracted so that the other cannot be attracted, an advancement controlling circuit for each way, a switch in each
- 35 advancement controlling circuit, means operated by the signal operating mechanism for closing said switch when the "stop" signal is displayed on its corresponding way, an advancement controlling switch for each circuit operable upon a predetermined positioning of its corresponding armature, and means to advance the signal operating means with respect to the driving means when an advancement controlling circuit is closed whereby to cause cancellation of substantially all of the unexpired portion of a then effective prechange interval.
- 45

8. A traffic control system for intersecting ways having, in combination, a set of "stop" and "go" signals for each way, signal operating

- 50 mechanism and driving means therefor normally acting to change the signals in timed sequence, with predetermined timed intervals between changes, an advancement controlling circuit for each way, means for energizing an advancement controlling circuit upon approach of a vehicle to the "stop" signal on its corresponding way, and means operated by said circuit to advance the operating mechanism with respect to the driving means whereby to cause cancellation of substantially all of the unexpired portion of a then effective prechange interval.
- 55

9. A traffic control system for intersecting ways having, in combination, a set of "stop" and "go" signals for each way, operating mechanism

- 60 normally acting to change the signals in orderly sequence, driving means for causing said mechanism to effect such changes with pretimed intervals therebetween, vehicle responsive means for each way, an initiating device for each way responsive associated with the respective vehicle responsive means and having interlocking mechanism to prevent simultaneous operation of more than one initiating device, and means controlled by the initiating devices for advancing the operating mechanism with respect to the

driving means whereby to cause cancellation of substantially all of the unexpired portion of a then effective prechange interval.

10. A traffic control system for intersecting ways, having, in combination, a set of "stop" and "go" signals for each way, signal operating mechanism and driving means therefor acting normally to change the signals in an uninterrupted timed sequence, with predetermined timed intervals between changes, advancing mechanism including a device driven synchronously with the operating mechanism, and traffic responsive advance initiating means for causing actuation of said device to move the operating mechanism in advance of the driving means whereby to cause cancellation of substantially all of the unexpired portion of a then effective prechange signal.

11. A traffic control system for intersecting ways having, in combination, a set of "stop" and "go" signals for each way, signal operating mechanism and driving means therefor acting normally to change the signals in timed sequence, with predetermined timed intervals between changes, advancing mechanism including a cam normally driven by the operating mechanism, a normally inactive cam follower, and means operated by approach of a vehicle to move the same follower to drive the cam, and thereby to advance the operating mechanism with respect to the driving means whereby to cause cancellation of substantially all of the unexpired portion of a then effective prechange interval.

12. A traffic control system for intersecting ways having, in combination, a set of "stop" and "go" signals for each way, signal operating mechanism and driving means therefor acting normally to change the signals in timed sequence, with predetermined timed intervals between changes advancing mechanism including a device driven synchronously with the signal operating mechanism, advancement controlling circuits, one for each way, vehicle responsive means having provision for energizing one or the other of said advancement controlling circuits, a magnet in each advancement controlling circuit associated with to effect acceleration of the synchronously driven device to drive the signal operating mechanism ahead of the normal timed control whereby to cause cancellation of substantially all of the unexpired portion of a then effective prechange interval.

13. A traffic control system for intersecting ways having, in combination, a set of "stop" and "go" signals for each way, signal operating mechanism, driving means for the signal operating mechanism normally acting to change the signals in timed sequence, an initiating circuit for each way, vehicle responsive means for each way to energize the initiating circuit, each initiating circuit including an electro-magnet, relay armatures for the magnets, means for interlocking said armatures when one is attracted so that the other cannot be attracted, means for retarding retraction of an armature after being attracted, means for opening an initiating circuit for a time sufficient to permit complete retraction of an armature prior to the change from the "go" to the "stop" signal, an advancement controlling circuit for each way having a switch operable responsive to the signal operating mechanism except when the "stop" signal is displayed for rendering said advancement controlling circuit ineffective, means for ener-

gizing an advancement controlling circuit by energization of its corresponding initiating circuit, and means acting upon energization of and advancement controlling circuit to advance the signal operating mechanism ahead of the driving means.

14. A traffic control system for intersecting ways having in combination, a right of way signal device including a set of signals for each way for manifesting "stop" and "go" aspects therefor, means including signal control mechanism for normally changing the aspects of said signals in orderly sequence and driving means for causing said mechanism to effect such changes with predetermined intervals therebetween, traffic responsive means associated with respective ways each operable during a "go" aspect for some other way for advancing the signal control mechanism with respect to the driving means to cause cancellation of substantially all of the unexpired portion of the interval determined pursuant to the pretiming to precede termination of such "go" aspect and for establishment of a "go" aspect for the way of such operated means, and change delay means associated with the traffic responsive means for each way and operable during a "go" aspect for its associated way for delaying any such cancellation.

15. A traffic control system for intersecting ways having in combination, a right of way signal device including a set of signals for each way for manifesting "stop" and "go" aspects therefor, means including signal control mechanism for normally changing the aspects of said signals in orderly sequence and driving means for causing said mechanism to effect such changes with predetermined intervals therebetween, traffic responsive means associated with respective ways each operable only following a predetermined portion of a "go" aspect for some other way for advancing the signal control mechanism with respect to the driving means to cause cancellation of substantially all of the unexpired portion of the interval allotted to such "go" aspect pursuant to the pretiming, thereby to hasten establishment of a "go" aspect for the way of such operated means, and change delay means associated with the

traffic responsive means for each way and operable during a "go" aspect for its associated way for delaying any such cancellation.

16. A traffic control system for intersecting ways having, in combination, a right-of-way signal device including a set of signals for each way, signal control mechanism for changing the signals in orderly sequence, driving means for causing said mechanism to effect such changes with predetermined timed intervals therebetween, an initiating circuit for each way, an advancement controlling circuit for each way, means acting upon closure of an initiating circuit tending to close the corresponding advancement control circuit and to prevent concurrent closure of the other advancement controlling circuit, and means operable upon closure of an advancement controlling circuit for advancing the signal control mechanism with respect to the driving means to cause cancellation of substantially all of the unexpired portion of the then effective prechange interval.

17. A traffic control system for intersecting ways having, in combination, a right-of-way signal device including a set of signals for each way, signal control mechanism for normally changing the signals in orderly sequence, driving means for causing said mechanism to effect such changes with predetermined intervals therebetween, an initiating circuit for each way, means for automatically closing the initiating circuit upon approach of a vehicle, an advancement controlling circuit for each way, interlocking means operated by the initiating circuit to close the respective advancement controlling circuits and to prevent concurrent closure of both of said advancement controlling circuits, means operable upon closure of an advancement controlling circuit for advancing the signal control mechanism with respect to the driving means to cause cancellation of substantially all of the unexpired portion of the then effective prechange interval, and means for preventing closure of an advancement controlling circuit during a predetermined part of the time interval associated therewith.

VERNON DURBIN.
